CLAIM

The ornamental design for a pull-up bar substantially as shown and described.

DESCRIPTION

FIG. 1 is a top, front, right side isometric view of a pull-up bar.

FIG. 2 is a bottom, rear, left side isometric view of the pull-up bar of FIG. 1.

FIG. 3 is a front elevation view of the pull-up bar of FIG. 1.

FIG. 4 is a rear elevation view of the pull-up bar of FIG. 1.

FIG. 5 is a left side elevation view of the pull-up bar of FIG. 1.

FIG. 6 is a right side elevation view of the pull-up bar of FIG. 1.

FIG. 7 is a top plan view of the pull-up bar of FIG. 1.

FIG. 8 is a bottom plan view of the pull-up bar of FIG. 1; and,

FIG. 9 is a top, front, right side isometric view of the pull-up bar of FIG. 1 in an environment of a fitness device.

The broken lines in FIGS. 1-8 illustrate unclaimed features of the design and form no part of the claimed design. The broken lines in FIG. 9 within the bounds of the pull-up bar illustrate unclaimed features of the design and form no part of the claimed design. The additional broken lines in FIG. 9, outside the bounds of the pull-up bar, are for purposes of illustrating use and environment only and form no part of the claimed design. The pairs of wavy lines throughout the figure views are symbolic break lines in the length and/or width of the pull-up bar and any portion within the symbolic break lines form no part of the claimed design.
